UNITED STATES PATENT OFFICE.

THOMAS C. ANGERSTEIN, OF CHICAGO, ILLINOIS.

DESIGN FOR A ROAD-MARKER.

57,568.

Specification for Design.

Patented Apr. 26, 1921.

Application filed August 19, 1920. Serial No. 404,688. Term of patent 14 years.

To all whom it may concern:

Be it known that I, THOMAS C. ANGERSTEIN, a citizen of the United States, residing at Chicago, in the county of Cook and State of Illinois, have invented a new, original, and ornamental Design for a Road-Marker, of which the following is a specification, reference being had to the accompanying drawing, forming a part thereof.

The figure is a face view of the road marker showing my new design.

I claim:

The ornamental design for a road marker, as shown.

THOMAS C. ANGERSTEIN.
